UNITED STATES PATENT OFFICE.

LANSING ONDERDONK, OF NEW YORK, N. Y., ASSIGNEE TO UNION SPECIAL MACHINE COMPANY, OF CHICAGO, ILLINOIS, A CORPORATION OF ILLINOIS.

BLINDSTITCH SEWING-MACHINE.

1,132,966.

Specification of Letters Patent. Patented Mar. 23, 1915.

Application filed December 6, 1907. Serial No. 405,359.

To all whom it may concern:

Be it known that I, LANSING ONDERDONK, a citizen of the United States, residing at New York city, in the county of New York, State of New York, have invented certain new and useful Improvements in Blind-stitch Sewing-Machines, (Case F,) of which the following is a description, reference being had to the accompanying drawing and to the letters and figures of reference marked thereon.

My invention relates to new and useful improvements in blind stitch sewing machines, and has for its object to provide a compact arrangement of the stitch forming elements.

In the drawings which show by way of illustration, one embodiment of my invention:—Figure 1 is a sectional view of the overhanging arm showing my improved arrangement of stitch forming mechanism. Fig. 2 is a front elevation of the overhanging arm, with the face plate removed. Fig. 3 is a detail of the needle operating link. Fig. 4 is a detail, showing the arrangement of the cranks for operating the looper and spreader.

The work support 1 is provided with a crimping ridge 2, over which the fabric is bent, so that the needle may enter and emerge on the same face of the fabric. The overhanging arm 3 has mounted therein a main shaft 4, from which the stitch forming elements receive their motion. A needle 5 is carried by a needle lever 6, which is pivoted at 7 to a stud projecting from the lower end of the needle head, supported on the overhanging arm. Said needle lever is also provided with a ball stud 8, to which is connected one end of a link 9. The main shaft 4 is provided with an eccentric 10, which engages the other end of the link 9. It will be noted that the eccentric which operates the needle lever is located in the forward end of the overhanging arm, and that the link or eccentric strap 9 extends down closely beside the needle head, so that the entire portion of the machine underneath the overhanging arm is free and unobstructed. The shaft 4 is extended beyond the eccentric 10 into a bearing 11 formed in the overhanging arm. Said shaft has mounted thereon a bevel gear 12 which is secured to the shaft by a suitable set screw 13. A vertical shaft 14 is mounted in a bearing 15

secured by the screws 16, 16, to the overhanging arm. The upper end of the shaft 14, carries a bevel gear 17 which meshes with the bevel gear 12. The lower end of the shaft 14 carries a crank arm 18, on which is mounted a crank stud 19.

The loop spreader 20 is mounted in a bearing support 21, formed in a lug carried by the overhanging arm. The loop spreader is provided with a crank arm 22, at its upper end, which carries a stud 23 at its outer end. Said stud 23 is provided with spaced ears between which is pivoted a link 24. The opposite end of the link 24 has a universal connection with the crank pin 19.

The looper 25 is mounted in a bearing 26 secured to the head of the machine, and receives its oscillation from a crank arm 27, secured to the upper end of the looper support. Said crank arm 27 carries a stud at its outer end, which is provided with spaced ears and between said spaced ears is pivoted a link 28.

The crank pin 19 carries a laterally extending crank arm 29, at its lower end and at the outer end of said arm 29, is a second crank pin 30. One of these crank arms is timed ahead of the other, that is, the crank pin carried thereby is ahead of the other crank pin in the revolution of the vertical shaft and with relation to the forming of the stitch so that the looper is moved forward first and the spreader is then caused to oscillate to engage the looper thread. These crank arms are set in different horizontal planes so as to permit the crank pins to be freely connected to the parts which are operated thereby and the vertical shaft to make a complete rotation. The crank pin 30 is connected to the link 28 by a universal joint.

The operation of my device is as follows:—The needle is reciprocated back and forth across the work crimping ridge, and the thread carrying looper is oscillated so as to engage the needle loop. The loop spreader is then brought in contact with the looper thread, and carries the same across the line of seam into the path of the needle.

Having thus particularly described my invention, what I claim as new and desire to secure by Letters Patent is:—

1. The combination of a work support, an overhanging arm, a main shaft in said overhanging arm, a needle, a looper and a

spreader coöperating with each other to form stitches, devices located in the forward end of the overhanging arm for operating said needle, looper and spreader from said main shaft, said devices including a vertical shaft having a driving connection with said main shaft and driving connections with the looper and spreader.

2. The combination of a work support, an overhanging arm, a needle, a looper and a spreader, devices located in the forward end of the overhanging arm for operating said needle, said looper and said spreader, said devices including a vertical shaft and non-alined crank pins carried by said vertical shaft for operating said looper and said spreader.

3. The combination of a work support, an overhanging arm, a looper and a spreader, and means for operating said looper and spreader, including a shaft, a crank pin eccentrically mounted on the end of said shaft, an arm carried by said crank pin and a second crank pin carried by said last named arm, and means for connecting the spreader to one of said crank pins, and means for connecting the looper to the other of said crank pins.

4. The combination of a work support, an overhanging arm, a main shaft in said overhanging arm, a vertical shaft in said overhanging arm geared to said main shaft, a looper, a spreader, a crank arm carried by said vertical shaft for operating said spreader, an arm carried by said crank arm and a crank pin carried by said last named arm for operating said looper.

5. The combination of a work support, an overhanging arm, a main shaft in said overhanging arm, a vertical shaft in said overhanging arm geared to said main shaft, a looper, a spreader, a crank arm carried by said vertical shaft for operating said spreader, an arm carried by said crank arm,

and a crank pin carried by said last named arm for operating said looper, a needle lever pivoted to said overhanging arm, and devices operated from the forward end of the main shaft for operating said needle.

6. The combination of a work support, an overhanging arm, a main shaft in said overhanging arm, a vertical shaft in said overhanging arm geared to said main shaft, a looper, a spreader, a crank arm carried by said vertical shaft for operating said spreader, an arm carried by said crank arm, a crank pin carried by said last named arm for operating said looper; a needle lever pivoted to the overhanging arm, an eccentric on the main shaft at the forward end thereof and a link connecting said eccentric and said needle lever.

7. The combination with a work support, an overhanging arm, a main shaft in said overhanging arm, a vertical shaft in said overhanging arm geared to said main shaft, a looper, a spreader, a crank arm carried by said vertical shaft for operating said spreader, a crank pin carried by said crank arm and a second crank arm carried by said crank pin for operating said looper, one of said crank arms, being timed ahead of the other.

8. The combination of a work support, an overhanging arm, a main shaft in said overhanging arm, a vertical shaft in said overhanging arm geared to said main shaft, a looper, a spreader, a crank arm carried by said vertical shaft for operating said spreader, a second crank arm for operating said looper, said crank arms being in different horizontal planes.

In testimony whereof I affix my signature, in presence of two witnesses.

LANSING ONDERDONK.
